L. H. MORGAN.

AUDIBLE ALARM FOR VEHICLES.

APPLICATION FILED JAN. 24, 1918. RENEWED JUNE 22, 1920.

1,349,467.

Patented Aug. 10, 1920.

UNITED STATES PATENT OFFICE.

LEWIS HOWELL MORGAN, OF CLEVELAND, OHIO, ASSIGNOR TO THE AMERICAN AUTO ALARM COMPANY, OF CLEVELAND, OHIO, A CORPORATION OF OHIO.

AUDIBLE ALARM FOR VEHICLES.

1,349,467.

Specification of Letters Patent. Patented Aug. 10, 1920.

Application filed January 24, 1918, Serial No. 213,520. Renewed June 22, 1920. Serial No. 390,790.

To all whom it may concern:

Be it known that I, LEWIS H. MORGAN, a citizen of the United States, and a resident of Cleveland, in the county of Cuyahoga and

State of Ohio, have invented a new and Improved Audible Alarm for Vehicles, of which the following is a full, clear, and exact description.

This invention relates to safety appliances for vehicles, especially automobiles, and has particular reference to a means whereby the loud ring of a bell, or its equivalent, is caused to suddenly and unexpectedly take place when any unauthorized person attempts to move or remove the vehicle.

Among the objects of the invention, therefore, is to provide improved facilities whereby when the vehicle is left standing unguarded it may be so adjusted or equipped that it cannot be moved without authority without the sounding of a loud alarm, provision being made, however, for the adjustment of the alarm devices so that when the owner or other authorized person is about to start the vehicle the alarm devices are rendered inoperative.

More definitely stated this improvement includes a gong, means to ring the gong, and shiftable means controlling the action and position of the gong ringing devices with key controlled means to determine the position of the shifting devices.

A still further object is to provide an alarm device of the character above indicated that may be easily applied to any known or standard vehicle in which there is a rotating shaft.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical longitudinal section of the line 1—1 of Fig. 2 and

Fig. 2 is a vertical transverse section on the line 2—2 of Fig. 1.

Referring now more particularly to the drawings, I show at 10 one of the floor boards of the vehicle body beneath and par-

allel to which operates a rotating shaft 11 such for example as the transmission shaft between an automobile engine and the differential.

In some types of automobiles the shaft 11 is incased in a sleeve or housing 12 which ordinarily is stationary and within which the shaft 11 is adapted to rotate freely.

My improved mechanism is substantially all inclosed within a casing 13 secured to the bottom surface of the floor board 10, the end walls of the casing being provided with elongated openings or slots 14 through which the shaft 11 and its housing project loosely so as to provide freedom of movement vertically between the body of the vehicle and the transmission shaft.

15 indicates a gong supported upon a rigid standard 16 fixed to the rear wall of the casing in any suitable manner. Adjacent to the standard is a bracket 17 also secured to the same wall or which may constitute a part of the standard structure. The main or effective part of the bracket extends horizontally parallel to the standard 16 and is provided with a downwardly projecting arm 18 to which is secured a finger 19 which extends horizontally across the general plane of the gong.

Pivoted at 20 on the end of the bracket 17 is a lever 21 of the first class. At the rear end of this lever is pivotally secured at 22 a link 23 having pin and slot connection with a foot operated plunger 24 extending through a hole 25 in the floor board. The pin and slot connection 26 between the plunger and the link provides a certain amount of relative endwise movement between these two parts, but prevents relative rotation between them. The plunger is provided on one side with spaced notches 27 into which a key controlled locking bolt 28 is adapted to engage in alternation so as to positively hold the plunger either up as shown in full lines or down as shown in dotted lines. Except as just described the notched portion of the plunger is smooth and preferably cylindrical. With this part of the plunger a fixed guide 29 cooperates to maintain the plunger in erect position and hold it for proper cooperation with the locking bolt 28.

It is to be noted, however, that with the plunger locked as shown the link is adapted to reciprocate up and down as far as permitted by the pin and

slot connection. When the locking bolt is released a strong coil spring 30 having one end fixed to the finger 19 and the other end fixed at 31 to the lever 21 on the opposite side of the pivot 20 thereon from the link 23 tends to hold the link elevated.

The front end of the lever 21 has journaled in or upon it a long pinion 32 which when this end of the lever is down meshes with a master gear 33 clamped upon the shaft 11 and hence is rotated from the shaft when the vehicle is in motion. Fixed to the pinion 32 is a cross-head 34 to the ends of which are loosely hung or pivoted at 35 a pair of clappers 36 which are thrown out by centrifugal force when the pinion is rotated from the master gear and are so caused to strike violently against a gong. The pinion 32 is preferably considerably longer than the width of the master gear so as to insure proper coöperation between the two toothed members even though the shaft may have a certain amount of endwise movement with respect to the body in practice.

25 In order to clamp the master gear to the shaft 11 a gap 37 is cut out of the housing 12 on opposite sides of the gear 33. In order then to support the ends of the housing sections I provide a yoke 38 having two legs 30 clamped at 39 to the respective housing sections whereby the two sections are rigidly connected and prevent undue frictional contact with the driving shaft. The crotch portion of the yoke may coöperate with a casing in any suitable manner so as to obviate any tendency for the housing sections to rotate. To this end I indicate the yoke as projecting downwardly through a slot 40 in the bottom of the casing. It will thus be seen that there is no interference between the yoke and the housing with respect to relative vertical movements, but yet the yoke will prevent any rotation of the housing as well as holding the housing rigid.

45 When the owner or driver of the vehicle wishes to operate the vehicle he applies his foot to the plunger 24 forcing it down into the dotted line position where it will be locked by the key controlled bolt 28. This movement of the plunger acting through the link 23 will swing the lever 21 into the dotted line position and thus throw the pinion far enough above the master gear to insure that there can be no engagement between the pinion and the gear, and hence

there will be no possibility for the device under these conditions to cause the ringing of the alarm. When, however, he wishes to leave the vehicle unguarded he causes the plunger to assume the position shown in full lines leaving the spring 30 free to hold the pinion 32 in mesh with the master gear. Under these conditions, therefore, it is obvious that the rotation of the shaft due to the starting of the vehicle and the accompanying rotation of the pinion 32 will cause a violent ringing of the bell and so the surreptitious driver will not only be surprised, but the authorities along the street will likewise be apprised of the fact that something is wrong.

I claim:

1. In an alarm for vehicles, the combination with a master gear fixed to a rotating shaft and a gong adjacent thereto, of means coöoperating with the gong to ring the same including a pinion adapted to mesh with the master gear and means pivoted to the pinion to swing into engagement with the gong when the pinion rotates, and key controlled means to determine the position of the pinion with respect to the master gear.

2. In an audible alarm for vehicles, the combination with a rotating shaft, a master gear fixed thereto and a sounding device adjacent to the master gear, of a pinion adapted to mesh with the master gear and so be rotated therefrom, means pivoted to the pinion and actuated therefrom to cause the sounding of the sounding device when the pinion is rotated from the master gear, a lever to which the pinion is connected, means acting upon the lever tending to hold the pinion in mesh with the master gear, and means under the control of the owner of the vehicle serving to hold the pinion out of mesh with the master gear.

3. In an audible alarm for vehicles, the combination with a rotating shaft, a master gear fixed thereto and a gong adjacent to the shaft, of a pinion adapted to mesh with the master gear, a crosshead carried by the pinion, a pair of clappers pivoted to the ends of the crosshead and so caused to fly out by centrifugal force into striking engagement with the gong when the pinion is rotated, and means to control the position of the pinion with respect to the master gear.

LEWIS HOWELL MORGAN.
